Inventor:

Baker S. Ruddick

UNITED STATES PATENT OFFICE.

BAKER S. RUDDICK, OF COLUMBUS, INDIANA.

HARMONICA-HOLDER.

SPECIFICATION forming part of Letters Patent No. 366,260, dated July 12, 1887.

Application filed April 14, 1886. Serial No. 198,878. (Model.)

To all whom it may concern:

Be it known that I, BAKER S. RUDDICK, residing at Columbus, Bartholomew county, Indiana, have invented a new and useful instrument for holding the harmonica in the mouth without the use of the hands while playing some accompanying instrument, of which the following is a specification.

My invention is illustrated in the accompanying drawing, the figure representing a front view.

The invention which I call the "harmonica-holder" is made of spring-steel wire, and of different sizes, according to the necks of different persons.

The ends A A of the invention, as may be seen by the drawing, (filed April 14, 1886,) are intended to be sprung apart upon adjusting

the instrument to the neck and to hold the harmonica in the mouth.

B B B is a three-quarter-inch circle forming the neck part.

C C C is a triangular wing intended to be buttoned under the vest or coat to hold the instrument in its proper place.

What I claim is—

The harmonica-holder consisting of the open ring B B B, adapted to encircle the neck of the performer, the bent portions C C C, and the vertical arms provided with the points A A, substantially as set forth.

B. S. RUDDICK.
